UNITED STATES PATENT OFFICE.

ELBRIDGE R. HOLMES AND WALTER H. WAKEFIELD, OF WORCESTER, MASSACHUSETTS, ASSIGNORS TO CROMPTON & KNOWLES LOOM WORKS, OF WORCESTER, MASSACHUSETTS, A CORPORATION OF MASSACHUSETTS.

TUBE FRAME.

Application filed November 9, 1923. Serial No. 673,758.

This invention relates to improvements in tube frames for Axminster looms and an object of the invention is to provide a frame of increased stiffness to resist deflection when the yarn is being pulled off the spools during the weaving process.

Another object of the invention is to provide a hollow metallic frame so constructed as to afford a greater thickness of material for holding screws than is found in the hollow tubes at present in use.

A further object of the invention is to provide an all metal tube frame so constructed as to permit the use of removable sections of yarn tubes held detachably to the frame by fastening means each of which can be tightened without loosening any of the neighboring fastening means.

A still further object of the invention is to provide an improved means for securing the spool supporting bracket to a frame formed of a multiple of tubes in such a way as to hold the several tubes together.

With these and other objects in view, which will appear as the description proceeds, the invention resides in the combination and arrangement of parts hereinafter described and pointed out in the claims.

In the drawings, wherein one form of the invention is shown, .

Fig. 1 is a front elevation of a tube frame constructed according to our invention,

Fig. 2 is an enlarged vertical section on line 2—2 of Fig. 1,

Fig. 3 is an enlarged end elevation of the frame looking in the direction of arrow 3, Fig. 1,

Fig. 4 is a horizontal section taken on line 4—4 of Fig. 3,

Fig. 5 is a vertical section taken on line 5—5 of Fig. 3, and

Fig. 6 is a horizontal section on line 6—6 of Fig. 3.

In the drawings, a frame 10 carries end bearings 11 and intermediate bearings 12 on which are mounted spools 13. Yarn tubes 14 are grouped in relatively small units or sections 15, each of which comprises an angle portion 16 having a rib 17 formed on the vertical flange 18 thereof. A spring hook 19 is secured to each end of the frame.

In order to give greater stiffness to the frame 10, it is formed of a plurality of tubes, in this instance two, as 20 and 21,

and these tubes have their adjacent vertical walls secured together in any approved manner, as by soldering or welding to form a wall 22 thicker than the outer walls of the frame. In this way the vertical walls have substantially double the cross section of the frames formed of single tubes. The upper part of flange 18 of the angle portion 16 is perforated to receive screws 23 which are screwed into the wall 22. In order to prevent wall 24 of tube 20 from being bent inwardly under the influence of the screws 23, each of the latter is surrounded by a bushing 25 which bears at its inner end on wall 22 and has its outer end extended through wall 24. The bushings make it possible to tighten each screw without disturbing the setting of adjacent screws, as would be the case should the screw heads bear against wall 24.

The angle portion 16 is bent upwardly as at 26 and is held under screws 27 which are threaded into wall 22 and surrounded by bushings 28 similar in purpose and construction to bushings 25. By the construction described the screws 23 and 27 are threaded into the double wall 22 and the yarn tube sections are held to the composite tube frame very tightly with the strain of holding the sections absorbed by the bushings.

Another feature of our invention concerns the end brackets 29 which carry the bearings 11 and serve with spring hooks 19 to engage the chain (not shown) by means of which the successive tube frames are moved to weaving position. The brackets 29, one on each end of the frame, are identical and a description of one will suffice for both.

The upper end of the bracket is offset as at 30 and is slotted as at 31 to receive the upper end of spring hook 19. The lower end of the bracket is provided with two slots 32, one preferably on each side of the spring hook 19 and so placed as to receive ears 33 and 34 formed integrally, respectively, on tubes 20 and 21. Another slot 35 is formed in the bracket preferably below the spring hook 19 and receives a pair of ears 36 extending from and formed integrally with the component parts of wall 22. These ears are headed over as rivets, as shown in Figs. 4, 5 and 6, and hold the brackets very tightly to the tube. The ends of the tubes

20 and 21 between the ears fit snugly against the inner face of the lower end of the bracket, which latter is drawn tightly against the tube ends by the riveting of the 5 ears.

From the foregoing it will be apparent that our tube frame, being made of a plurality of hollow tubes, is stiffer than a frame made of a single tube and also affords screw 10 threads of greater length than is possible where a single thickness only is available. The screws 23 and 27 together with the three sided angle portion 16 assist in holding the tube sections together. Also, the bushings 15 permit each screw to be set up firmly without disturbing neighboring screws. Furthermore, the bracket is riveted to the metallic tubes by means of ears integral with the tubes, and serves to hold the ends 20 of the tube together independently of soldering or welding.

Having thus described our invention, it will be evident that changes and modifications may be made by those skilled in the 25 art without departing from the spirit and scope of the invention as set forth in the appended claims, and we do not wish to be otherwise limited to the details herein disclosed.

30 What we claim is:

1. A tuft yarn tube frame for Axminster looms comprising a plurality of tubes parallel to each other and extending longitudinally of the tube frame and having parallel walls, and means to secure adjacent walls of said tubes together so that each tube supports the other.
2. A tuft yarn tube frame for Axminster looms composed of a plurality of hollow frame tubes assembled in juxtaposition, a tuft yarn tube unit and means for holding said unit to the frame, said means passing through one frame tube and into the adjacent frame tube.
3. A tuft yarn tube frame for Axminster looms comprising a hollow composite metallic member having outer parallel walls and an inner wall between the outer walls co-operating with said outer walls to stiffen the member.
4. In a tuft yarn tube frame for Axminster looms, a frame composed of a plurality of tubes, tuft yarn tube units, and means to secure said units to said frame, said means extending through one of said tubes and secured in another of said tubes.
5. In a tuft yarn tube frame for Axminster looms, a frame composed of a plu-

rality of tubes, tuft yarn tubes, an angle section carrying said yarn tubes, to form a tuft yarn tube unit, said unit engaging a plurality of frame tubes, and means to secure different portions of the section to the different frame tubes.

6. In a tuft yarn tube frame for Axminster looms, a plurality of substantially similar frame tubes assembled in juxtaposition and having adjacent walls thereof secured to each other to form portions of the frame of increased thickness, a tuft yarn tube unit, and means passing through said unit, and entering adjacent walls to hold the unit to the frame.

7. A tuft yarn tube frame for Axminster looms formed with a hollow member, a tuft yarn tube unit, a screw passing from one wall of said member to another wall thereof and passing through said unit, and a bushing surrounding the screw and extending from said unit to the second named wall of said member, said bushing passing freely through the wall of the member adjacent the unit and supporting said screw.

8. A tuft yarn tube frame for Axminster looms composed of a plurality of hollow frame tubes assembled in juxtaposition, a tuft yarn tube unit, means for holding said unit to the tube frame, said means extending through one frame tube and into another, and means adjacent said holding means extending from the tuft yarn tube unit to a remote portion of the adjacent frame tube to take the strain of said holding means.

9. A tuft yarn tube frame for Axminster looms comprising a plurality of tubes having the inner walls thereof secured together to form a central wall for said frame, a tuft yarn tube unit having parallel sides to engage opposite walls of the frame, and retaining elements for said section passing through the said opposite walls of the frame and anchored in the said central wall.

10. A tuft yarn tube frame for Axminster looms formed of a plurality of hollow metallic frame tubes assembled in juxtaposition, ears formed integral with and projecting from the ends of the tubes, and a bracket for supporting said tube frame having openings therein to receive said ears, the ears being expanded into said openings to hold said bracket to the tubes.

In testimony whereof we have hereunto affixed our signatures.

ELBRIDGE R. HOLMES.
WALTER H. WAKEFIELD.
